OR D 1,745

D 1,745 Design for Floor Oil Cloths
Neil V Powers.

Patented March 31, 1963
Re-registered Feb 28, 1963

UNITED STATES PATENT OFFICE.

JOHN NEIL, OF CLINTON, MASSACHUSETTS, AND ALBERT E. POWERS, OF LANSINGBURG, NEW YORK, ASSIGNEES TO D. AND A. E. AND N. B. POWERS, OF LANSINGBURG, NEW YORK.

DESIGN FOR FLOOR-CLOTH.

Specification forming part of Design No. 1,745, dated March 31, 1863.

To all whom it may concern:

Be it known that we, JOHN NEIL, of Clinton, in the county of Worcester and State of Massachusetts, and ALBERT E. POWERS, of the town of Lansingburg, county of Rensselaer, and State of New York, have invented and produced a new and original Design for Floor Oil-Cloths or other Fabrics; and we do hereby declare that the following is a full and exact description of the same, viz:

The chief feature of the pattern consists of two broad bands of combined coloring of irregular breadth so arranged and placed that they appear to be interwoven diagonally of the fabric and the openings or intervals are of the form of a pointed cross. Along the edges of these bands is a narrow belt, differently colored from the principal body of the bands.

The ornamentation and coloring of the pat-

tern are of what is known as "Persian style," with moss-work introduced in certain portions of the bands.

The whole design, details, and coloring are shown on the accompanying drawings, which are hereby declared to be a part of this specification.

What we claim, and desire to secure by Letters Patent of the United States, is—

The design or pattern as shown upon the aforesaid drawings.

JOHN NEIL.
A. E. POWERS.
